Primary Examiner — T. Chase Nelson

(74) Attorney, Agent, or Firm — Banner & Witcoff, Ltd.

(57) CLAIMThe ornamental design for a shoe outsole, as shown and described.

DESCRIPTION

FIG. 1 is a front perspective view of a shoe outsole showing
my new design;

FIG. 2 is a bottom view thereof;

FIG. 3 is a rear perspective view thereof;

FIG. 4 is an enlarged view of FIG. 1 with unclaimed subject matter omitted;FIG. 5 is an enlarged view of FIG. 2 with unclaimed subject matter omitted; and,FIG. 6 is an enlarged view of FIG. 3 with unclaimed subject matter omitted.The broken line immediately adjacent to the shaded area represent an unclaimed peripheral boundary of the design.
The broken lines showing the remainder of the shoe in FIGS.
1-3 are for environmental purposes only and form no part of the claimed design.1 Claim, 6 Drawing Sheets(56)
